GAS COMPRESSOR

Gregory P. Cushing, Chicago, Ill.

Application March 10, 1947, Serial No. 733,467

12 Claims. (Cl. 230—108)

1

This invention relates to improvements in gas compressors, and more particularly to a gas compressor of the rotary, non-reciprocating type, or to a vacuum pump.

The primary object of the invention is to provide a novel, simple, inexpensive and efficient gas compressor operating by the centrifugal action of a rotor upon small bodies of a liquid fed thereto intermittently which serve to draw and trap gas in a receiver under pressure.

A further object is to provide a device of this character adapted to rotate at high speed, which is inherently and automatically balanced statically and dynamically under all operating conditions.

A further object is to provide a device of this character having means operating automatically to intermittently supply measured quantities of liquid to a centrifugal device for drawing a gas through discharge passages, wherein the means for measuring the liquid is located centrally in the centrifugal device so that it travels at low peripheral speed compared to the peripheral speed of the discharge portion of the device, thereby preventing excessive fluid turbulence in the operation of the device.

A further object is to provide a gas compressor of the type in which gas is pumped by the action of liquid moving under centrifugal force, wherein the separation of the gas from the liquid is accomplished under dynamic conditions with minimum separation losses.

A further object is to provide a device of this character, wherein gas under pressure pumped in the operation of the device flows in a counter centrifugal direction from the gas-liquid separation portion of the device to insure dehumidification of the gas.

A further object of the invention is to provide a gas compressor using liquid under centrifugal force as the pressure generating medium, wherein the liquid is trapped at a gas separation point from which it is discharged to a liquid outlet in a gradual flow under low pressure and with inherent kinetic energy acting upon the liquid to facilitate recirculation thereof.

Other objects will be apparent from the following specification.

In the drawing:

Fig. 1 is a transverse sectional view taken on line 1—1 of Fig. 2.

Fig. 2 is an axial sectional view of the device taken on line 2—2 of Fig. 1.

Referring to the drawing which illustrates the preferred embodiment of the invention, the nu-

meral 10 designates a substantially flat end wall of a casing, which wall is provided with a central circular aperture 11 therein. The end wall 10 is preferably of the shape best illustrated by the overall outline of the form of the device shown in Fig. 1. A flange 12 extends perpendicularly from the plate 10 at its margin and defines the outer wall of the casing. The casing has a rear wall 13 having a central aperture 14. The wall 13 forms the base of a cup-shaped casing part having an integral annular forwardly projecting flange or wall portion 15 formed at its margin and terminating in a planar or flat outwardly projecting flange 16 whose outer margin is of the same shape or contour as the flange 12 of the front wall of the casing and which is preferably secured at the edge of said flange 12 by securing members 17 which rigidly connect the casing parts together. The joint between the flanges 12 and 16 is sealed in any suitable manner as by the provision of sealing gaskets between the casing parts.

A pair of spaced coaxial bearings 20 and 21 are mounted in any suitable manner in fixed relation to the casing, and the bearing 21 journals a sleeve 22 from whose inner end projects an enlarged portion 23 having a peripheral groove 24 whereby the part 23 constitutes a pulley for a V belt (not shown). The pulley portion 23 is of a diameter slightly less than the diameter of the aperture 14 in the wall 13 of the casing, whereby the pulley 23 may extend freely into the casing. A rotor 25 is fixedly mounted upon the inner end of the pulley 23 within the casing adjacent to the wall 13 thereof and preferably parallel to the wall 13. The rotor 25 is of cup-shaped form and has a marginal flange 26 formed integrally therewith at its periphery and terminating in an annular lip portion 27 positioned adjacent to but spaced rearwardly from the wall 10 of the casing. The rotor parts 25, 26, 27 are all spaced, free and clear of the casing parts, whereby they are free to rotate within the casing without frictional contact therewith.

A tube 28 is fixed within the sleeve 22 at one of its ends and projects therefrom through the casing to terminate in a flared mouth portion 29 spaced outwardly from the casing wall 10. The tube 28 fixedly mounts a hub 30 which is journaled in the bearing 20 and which extends freely through the aperture 11 in the plate 10. A second rotor 31 in the nature of a disk is carried by the inner end of the hub 30 substantially centrally between and spaced from the inner face 55 of the rotor 25 and the plane of the outer or for-

ward surface of the annular flange 27 of the first rotor. The second rotor 31 has a plurality of equiangularly related radial bores 32 formed therein. The rotor has a circumferential groove 33 formed in the face thereof confronting the rotor 25 in spaced relation to its margin, and the outer ends of the bores 32 open at said groove 33. The inner ends of the bores 32 are open at the inner periphery of the rotor and each communicates with the interior of the tube 28 by means of a registering aperture 34 formed in the tube 28 and having an outwardly tapering contour as shown. The margin 35 of the rotor 31 is of reduced thickness and is rearwardly offset from the face of the rotor 31 which confronts casing wall 10, thereby providing an offset 35' therein at the periphery of the rotor which permits the marginal flange 35 to be positioned substantially centrally between the rotor 25 and its annular flange 27, as best seen in Fig. 2.

The tube 28 has a plurality of openings 36 formed therein in longitudinally spaced relation to the ports or openings 34 and communicating with the space between the rotors 25 and 31. An outlet tube 37 projects into the tube 28 and terminates short of the openings 36 of said tube. The tube 37 is preferably stationary and is journaled within the tube 28 and leads to any suitable gas discharge outlet.

A partition 38 extends transversely across the tube 28 between the two series of openings 34 and 36 to bar passage of fluid through said tube 28. The member 36 is fixedly secured to the tube 28 to rotate therewith and has fixedly secured concentrically therewith a tube 39 of smaller diameter than tube 28 and projecting toward the inlet end of said tube as illustrated in Fig. 2. The portion 40 of the tube 39 is of increased thickness and outer diameter and has a plurality of equispaced passages 41 extending radially therethrough, each in axial alignment with one of the radial bores 32 of the rotor 31. A liquid intake pipe 42 connected with a fluid circulating system projects into the sleeve 39 which is freely rotatable therearound. The tube 42 terminates at 43 in outwardly spaced relation to openings 41 in the member 40 for the major portion of its extent, but at one or more portions 44 thereof the tube 42 extends substantially into engagement with the partition 38, said portion or portions 44 each being of a circumferential dimension adapted to close off a selected number of the ports 41. The liquid circulating system, of which the pipe 42 constitutes the outlet, is preferably connected at an outlet portion 45 of the convoluted casing wall 12 by the inlet conduit 46 shown in Fig. 1.

In the operation of the device, a belt is trained around the pulley 23, 24 and is driven at desired speed for the purpose of rotating the pulley and its associated parts. It will be understood, however, that while provision for a belt drive has been shown herein for purposes of convenience, a gear drive or any other desired type of drive may be used instead of the belt drive. Rotation of the pulley 23 is transmitted to the rotor, 25, 26, 27 carried by the pulley 23 and is also transmitted through the rotation of the tube 28 to the rotor 31 and the sleeve 39. The arrangement is such that rotation of the rotor 25, the rotor 31 and the sleeve 39 is the same; that is, that these parts operate at the same number of revolutions per minute. The speed at which the parts rotate may be any speed selected, depending upon the desired gas pressure to be developed but must

be a speed sufficient to produce centrifugal action. The lines 42, 46 of the liquid recirculating system may be connected with a reservoir of liquid (not shown) if desired, or the system may otherwise have a supply of liquid interposed therein. For the purposes of this invention any liquid may be used, although water is preferred in most instances. The water is supplied through the inlet pipe 42 at low pressure and discharges therefrom at the cut-out portion thereof defined by the end 43 of the tube, for passage by centrifugal force through those ports 41 of the sleeve 39 which register with the cut-out or cut-outs of the tube 42. The projection or projections 44 are so arranged and are of such circumferential size that when the device is operating at a predetermined speed dependent upon the pressure desired to be generated, the flow of liquid to each of the ports 41 will be cut off momentarily in successive sequence circumferentially during each revolution of the sleeve 39. This permits the formation of globules or masses 47 of the liquid which are discharged radially from the port 41 into the aligned port 34 of the tube 28 for discharge radially outwardly through the communicating bore 32 of the rotor. Such globules of liquid have been designated in different positions and in the process of formation in Fig. 2. At the time that the projection or projections 44 of the tube span any selected port 41 in the sleeve 39, gas, such as air, which is introduced through the lefthand end of the tube 28, is free to pass through the port 34 into the aligned bore 32 of the rotor. The globules of liquid 47 travel outwardly into and through the bores 32 of the rotor by virtue of centrifugal action and create therebehind in each of the bores a suction effect which serves to draw the gas therein. Thus during each revolution of the rotors, a charge of gas will be drawn into the inner end of each bore 32 by the suction action of the moving globule 47. In this connection it will be understood that, if two projections or cut-offs 44 are provided, then there will be two charges of gas introduced in each revolution of the rotor. The cut-offs 44 should be so correlated with the rotor that at least one globule 47 of liquid is contained in each rotor bore 32 at all times. This prevents gas discharge through the bores 32 counter-centrifugally. Where the device is used for the purpose of compressing air, the lefthand end of the tube 28 is open to atmosphere for free entry of air into the tube as illustrated. In cases where other gases are to be compressed, the compressor may be positioned within the low pressure gas container, or a suitable reservoir (not shown) for the gas may be fixedly associated with the housing of the compressor surrounding tube 28, the pipe 42 passing therethrough with a sealed fit, as will be obvious to those skilled in the art.

The liquid globules 47 which are forced through the bores 32 by centrifugal action are discharged at the mouths of the bores opening at the groove 33 in the rotor. Note in Fig. 2 that the radius of the outermost portion of the groove 33 is substantially equal to the inner radius of the annulus 27 of the rotor 25. Consequently, in the operation of the device, the continued radial discharge of the water globules 47 forms a body of liquid 48 at the margin of the rotor 25 which is trapped by the annulus 27, so that the margin 35 of the rotor 31 is traveling in said body of water 48. The gas which is withdrawn by suction through the bores 32 behind each of the

globules 47 is prevented from passing around the periphery of the rotor 31 by the liquid seal afforded by the positioning of the rotor margin 35 in the trapped liquid 48. Consequently, this air must travel through the passage 49 between the rotors 31 and 25 in a counter-centrifugal movement for discharge through the ports 36 into the outlet tube 37. In other words, the body of liquid 48 at the margin of the rotor 25 forms a liquid seal for the entrapped air, which seal is effective as long as the rotors continue to operate at a speed sufficient to exert centrifugal action upon the liquid in the device. As water is continually added to the body 48 at the margin of the rotors incident to operation of the device, it is bled off or spills over the lip of the annulus 27 into the convoluted passage 58 whose shape is determined by the outer wall 12 of the casing part 18. This water has a certain kinetic energy due to the operation of the rotor and travels to the outlet 45 of the convoluted passage for discharge into the conduit 46 under low pressure to provide for recirculation thereof to the inlet conduit 42 associated with the conduit 46 in the liquid recirculating system.

It will be apparent that if the air or other gas which is drawn through the device and compressed thereby has any moisture content, due either to its humidity or to the presence of the liquid globules 47, that moisture content is removed in the operation of the compressor. The moisture content of the gas is subject to the centrifugal action which causes it to be discharged into and become a part of the liquid 48 trapped in the rotor. Thus, in addition to the pumping of the air or other gas in the operation of the device, there is an efficient dehumidification of the gas under dynamic conditions which is characterized by minimum separation losses. In other words, the moisture content of the gas is discharged centrifugally, whereas the gas itself is sealed against centrifugal discharge in the event it is subject thereto, and a pressure is built up in the chamber 49 whose only outlet is in a counter-centrifugal direction through the openings 36 in the device.

Another factor of importance in the operation of the device is that the projections or cut-offs 44 and the ports 41 of the device which govern the formation and the size of the liquid globules 47 are positioned centrally of the device, whereby said ports 41 rotate relatively to the cut-offs 44 at low peripheral or linear speed compared to the peripheral or linear speed of the other rotating parts of the device. This results in a smooth globule-forming action with minimum tendency to create turbulence of either the liquid or the air through which the globule passes for entry through the port 34 into the aligned bore 32 of the rotor.

Still another feature of the device which is of considerable importance is that, assuming that the construction of the device is such that the rotating unit of the device is inherently balanced both statically and dynamically, that balance is not disturbed during the operation of the device. This is accomplished by virtue of the fact that each of the bores 32 has some water therein at all times by virtue of the fact that the cut-offs 44 are of limited arcuate extent and limit to a small portion of each revolution the time during which air or other gas may enter said bores. The retention of this operating balance facilitates high speed operation of the compressor and reduces the likelihood of vibration and chat-

ter or other conditions which would tend to produce undesirable wear of the parts of the device.

While the device has been illustrated herein with the hub 30 fitting freely and with clearance in the casing opening 11, and with the pulley 23 similarly freely fitting in the casing opening 14, it will be obvious that suitable journals or bearings may be provided at these points.

While only one form of the compressor has been illustrated and described herein, it will be understood that changes may be made therein within the scope of the appended claims without departing from the spirit of the invention.

I claim:

1. A gas compressor comprising a casing having a peripheral liquid outlet port, a tube extending axially through said casing and rotatable relative thereto, a pair of rotors fixed on said tube within said casing, one of said rotors being cup-shaped and having an inwardly projecting annular flange at its margin, the other rotor fitting within and spaced from said cup-shaped rotor and being of a diameter greater than the inner diameter of said flange, said second rotor having a plurality of equispaced bores open at their inner ends at its center and at their outer ends at the side of the rotor inwardly spaced from its periphery and confronting said first rotor, said tube communicating with a supply of gas and having a set of openings communicating with the inner ends of said bores, means positioned centrally of said rotor for successively injecting measured quantities of a liquid into said bores during rotation of said rotor, said tube having a second set of openings for exhaust of gas discharged into the space between said rotors, a barrier in said tube between said two sets of openings, and means for collecting gas discharged into said tube through said second set of tube openings.

2. A gas compressor comprising a casing having a peripheral liquid outlet port, a pair of spaced concentric rotors in said casing each having a hollow hub projecting from said casing, one rotor having a plurality of equispaced bores each open at its inner end at said hub and open at its outer end at the side face confronting the other rotor in spaced relation to the rotor periphery, means located in the hub of said rotor for successively introducing measured quantities of liquid into said bores during rotation of said rotor, the other rotor having a peripheral flange fitting freely around said first rotor and terminating in an annular flange whose inner edge is spaced outwardly from the outer ends of said bores and inwardly from the periphery of said first rotor, the hub of the first rotor communicating with source of gas, means projecting into the hub of the second rotor for collecting gas discharged into the space between said rotors, and means for rotating said rotors.

3. A gas compressor comprising a casing having a peripheral liquid outlet port, a pair of spaced concentric rotors in said casing each having a hollow hub projecting from said casing, the hub of one rotor communicating with a source of gas, said rotor having a plurality of substantially radial bores each open at said hub and discharging inwardly of its periphery at the face of said rotor confronting the other rotor, the other rotor having a rim spaced from and defining an annular channel fitting around the marginal portion of said first rotor outwardly of the discharge ends of said bores, a gas receiver communicating with the hub of the last named rotor, means

in the hub of said first rotor for successively feeding measured quantities of liquid into said rotor bores, and means for rotating said rotors, said rim channel serving to centrifugally trap a body of liquid into which margin of the bored rotor projects to form a gas retaining seal.

4. A gas compressor comprising a casing having a peripheral liquid outlet, an impeller in said casing having a hollow hub projecting from said casing and communicating with a source of gas, said impeller including a disc having passages each open at said hub and at one face thereof spaced inwardly from its periphery, means in said hub for intermittently feeding measured quantities of liquid into each passage, a cup-shaped retainer in said casing having a hollow hub projecting from said casing and communicating with a gas receiver, said retainer confronting the outlets of said passages and having an inwardly bent marginal portion extending around and spaced from the marginal portion of said disc and terminating outwardly of the outer ends of said passages, and means for rotating said impeller and said retainer.

5. A gas compressor comprising a casing having a peripheral liquid outlet, an impeller disc rotatable in said casing and having a tubular hub projecting from said casing and communicating with a source of gas, said impeller having a plurality of substantially radial passages open at said tubular hub and having their outlets at a side face of said disc spaced inwardly from its periphery, a rotor concentric with and confronting the outlets of said impeller and having an annular marginal channel opening inwardly and receiving with clearance the marginal portions of said impeller located outwardly of the outlets of said passages, said rotor having a tubular gas-receiving hub projecting from said casing, means for periodically feeding to each impeller passage a small quantity of liquid, and means for rotating said impeller and rotor.

6. A gas compressor comprising a casing having a peripheral liquid outlet, an impeller disc rotatable in said casing and having a tubular hub projecting from said casing and communicating with a source of gas, said impeller having a plurality of substantially radial passages open at said tubular hub and having their outlets at a side face of said disc spaced inwardly from its periphery, a rotor concentric with and confronting the outlets of said impeller and having an annular marginal channel opening inwardly and receiving with clearance the marginal portion of said impeller spaced outwardly from said passage outlets, said rotor having a tubular gas-receiving hub projecting from said casing, means for periodically feeding to each impeller passage a small quantity of liquid, said impeller and rotor being fixedly secured together as a unit, and means for rotating said unit.

7. A gas compressor comprising a casing having a peripheral liquid outlet, an impeller disc rotatable in said casing and having a tubular hub projecting from said casing and communicating with a source of gas, said impeller having a plurality of substantially radial passages open at said tubular hub and having their outlets at a side face of said disc spaced inwardly from its periphery, a rotor concentric with and confronting the outlets of said impeller and having an annular marginal channel opening inwardly and receiving with clearance the marginal portion of said impeller radially outwardly spaced from said outlets, said rotor having a tubular gas-receiving

hub projecting from said casing, means for periodically feeding to each impeller passage a small quantity of liquid, said impeller and rotor being fixedly secured together as a unit, and a drive pulley carried by one of said projecting tubular hubs.

8. A gas compressor comprising a casing having a peripheral liquid outlet, an impeller disc rotatable in said casing and having a tubular hub projecting from said casing and communicating with a source of gas, said impeller having a plurality of substantially radial passages open at said tubular hub and having their outlets at a side face of said disc spaced inwardly from its periphery, a rotor concentric with and confronting the outlets of said impeller and having an annular marginal channel opening inwardly and receiving with clearance the marginal portion of said impeller, said rotor having a tubular gas-receiving hub projecting from said casing, means for periodically feeding to each impeller passage a small quantity of liquid, and means for rotating said impeller and rotor, said liquid feeding means including a sleeve secured concentrically within said impeller hub and rotatable therewith, said sleeve having a plurality of apertures each substantially aligned with one of said impeller passages, and a stationary liquid conduit fitting snugly within said sleeve and having a lateral outlet of limited circumferential extent communicating with at least one of said sleeve apertures at all times.

9. A gas compressor comprising a casing having a peripheral liquid outlet, an impeller disc rotatable in said casing and having a tubular hub projecting from said casing and communicating with a source of gas, said impeller having a plurality of substantially radial passages open at said tubular hub and having their outlets at a side face of said disc spaced inwardly from its periphery, a rotor concentric with and confronting the outlets of said impeller and having an annular marginal channel opening inwardly and receiving with clearance the marginal portion of said impeller, said rotor having a tubular gas-receiving hub projecting from said casing, means for periodically feeding to each impeller passage a small quantity of liquid, and means for rotating said impeller and rotor, said liquid feeding means including a sleeve carried by and positioned concentrically within said impeller hub to define an annular space therearound and having a circumferential series of apertures each aligned with one of said impeller passages, a stationary liquid supply conduit projecting into said sleeve, and a cut-off member carried by said conduit and positioned to span and close a selected number of said sleeve apertures.

10. A gas compressor comprising a casing having a peripheral liquid outlet; a rotor in said casing, said rotor having spaced axial gas inlet and outlet passages, a plurality of radial impeller passages communicating with said inlet, and a radial transfer passage communicating with said outlet passage, said impeller passages communicating with said transfer passage at a point spaced inwardly from the outer part of said transfer passage, said transfer passage being open at one side of the peripheral portion of said rotor and return bent at its outer portion and radially outwardly of the points of communication of said impeller passages therewith; means for driving said rotor; and means in said inlet for successively feeding measured quantities of liquid into said impeller passages.

11. A gas compressor comprising a casing having a peripheral liquid outlet; a rotor in said casing, said rotor having spaced axial gas inlet and outlet passages, a plurality of radial impeller passages communicating with said inlet, and a radial transfer passage communicating with said outlet passage, said impeller passages communicating with a radially intermediate portion of said transfer passage, said transfer passage being open at the peripheral portion of said rotor and said rotor including a bent annular marginal lip spaced radially outwardly relative to the points at which said impeller passages communicate with said transfer passage and defining a liquid trap in said transfer passage; means for injecting measured quantities of liquid at the inner ends of said impeller passages; and means for driving said rotor.

12. A gas compressor comprising a casing having a peripheral liquid outlet; a rotor in said casing, said rotor having a plurality of passages therein including axial gas inlet and outlet passages, radial impeller passages communicating

with said gas inlet and a transverse transfer passage communicating with said outlet and open at the peripheral portion of said rotor, said impeller passages communicating with radially intermediate portions of said transfer passage; means carried by said rotor defining a liquid trap in said transfer passage located radially outwardly of the points of communication of said impeller passages with said transfer passage, means for introducing measured quantities of liquid in said impeller passages successively; and means for driving said rotor.
